Specification for Design.

Patented May 29, 1917.

Application filed March 7, 1917. Serial No. 153,200. Term of patent 7 years.

To all whom it may concern:

Be it known that I, JACOB ROTHLSBERGER, a citizen of the United States of America, and a resident of Muncie, in the county of Delaware and State of Indiana, have invented a new, original, and ornamental Design for Spoons, Forks, or Similar Articles, of which the following is a specification, reference being had to the accompanying drawings, forming part thereof.

Figure 1 is a front view of a spoon showing the improved design, tines of a fork being represented in dotted outline.

Fig. 2 is a side view of the same.

Fig. 3 is a back view of the same.

Fig. 4 is a cross-sectional view of the handle taken at the upper end thereof.

I claim:

The ornamental design for a spoon, fork, or similar article as shown.

J. ROTHLSBERGER.
